SLIDER FOR SEPARABLE FASTENERS

Vojtěch Puc, Prague-Vinohrady, Czechoslovakia,
assignor to Waldes Koh-I-Noor, Inc., Long
Island City, N. Y., a corporation of New York

Application August 25, 1936, Serial No. 97,730
In Czechoslovakia December 7, 1935

6 Claims. (Cl. 24—205)

My invention relates to fasteners of the slide-operated type having rows of interlocking elements mounted on flexible fabric tapes or stringers. More particularly my invention relates to distortion-resisting means rigidly built-in or forming part of the slider for automatically preventing unintended self-actuated movement of the slider in a direction parallel to the opening between the interlocking elements in a direction 5 toward the elements which are interlocked, such movement being frequently induced when the fabric tapes or stringers are spread apart at their free ends, for instance, by a force supplied laterally at or beyond the point where the elements 10 are interlocked.

For convenience, I will, in this specification, refer to that part of the structure where the stringers are united, whether the elements are in locked or unlocked position, as the lower portion 15 of the structure, while the opposite end will be referred to as the upper portion, and similarly, that portion of the slider which extends in the direction of the interlocked elements will be referred to as the lower portion of the slider, 20 while its opposite portion will be referred to as the upper portion of the slider. So also when I speak of a region beyond the slider, I mean the upper portion of the structure beyond the point where the elements are locked together. When 25 I speak of depending portions of the slider I refer to portions extending from one of the two slider plates, top or bottom, toward the other, irrespective of whether the plate from which the projection depends is, in use, the top or the 30 bottom plate.

In the usual construction of slide fasteners of the interlocking type there is employed a slider having lateral flanges, and an inner triangular member, said slider straddling the fastener elements, the flanges serving as camming elements, so that when the slider is pulled along the stringer tapes toward the upper portion of the structure, the elements will be caused to interlock, whereas, when moved in the opposite direction, the elements will be caused to become unlocked. However, the slider can be self-actuated by a lateral pull upon the stringers at points beyond the slider, so that the fastener structure becomes opened, any further pull upon the stringers aggravating the condition. Means for locking the slider in position such as a pin forming a part of the pull member of the slider have heretofore been used but this type of structure requires voluntary action by the operator in making it effective to perform its function. It has also been

suggested to bend or notch the forward edges of the slider flanges in a direction toward the longitudinal axis of the slider, but this type of structure proved impractical in that its effectiveness was soon destroyed by the frictional contact 5 with the elements.

It is the object of my invention to provide means for preventing the unintended, self-actuated movement of the slider by a construction of the slider which is such that it becomes automatically and reliably locked against movement, i. e. without the necessity of any volitional action on the part of the operator, whenever the slider is brought to rest in its position after interlocking the fastener elements, preventing movement 10 of the slider in the direction of the opening when any force is applied laterally of the stringers, either at the position of the slider or at points above such position.

My novel structure of slider, while effectively 20 performing the automatic locking function just described, is not in any manner hindered in its sliding movement when performing its function as a camming member in interlocking the fastener elements. Nor is its free movement during 25 the unlocking of the fastener elements interfered with in any manner. The slider is capable of being shifted in either direction along the edges of the stringers by a slight force applied to the slider longitudinally of such edges, but will automatically 30 be prevented from any unintentional movement along the edges of the stringers by any force applied laterally of such edges.

In accordance with my invention I provide the slider with integral dependent portions in the 35 region of its upper end, said dependent portions extending in a direction from one of the slider plates toward the other as distinguished from a structure in which the dependent element-engaging projections extend toward the longitudinal 40 axis of the slider. This feature of the new construction results in a strengthened or buttressed condition of the dependent portions in that, when such dependent portions are constituted of bent metal, the line of the bend will stand at right 45 angles to the longitudinal axis of the individual elements while when the dependent portions are formed by punching, they obtain their necessary strength and rigidity from the circumstance that they are hollow and therefore, like a tube, stronger 50 than a corresponding pin or rod.

In accordance with one embodiment of my invention I provide forward of the slider flanges which form the camming channel, depending projections which establish notches between them-

selves and the slider flanges, such projections being adapted to become interposed between successive fastener elements when the stringers are forcibly spread apart, in which event one of the 5 fastener elements will enter the notch and abut against the face of the projection. In this embodiment of the invention the dependent portions and notches appear forward of both of the flanges of the slider. Such structure is adapted for use 10 with a slide fastener arrangement of the usual type in which the tops as well as the bottoms of the interlocking elements are exposed.

In the type of fastener structure in which the 15 interlocking elements are covered by a fabric material when they have been interlocked, to which a second embodiment of my invention is applicable, the dependent projections and notches appear only on the bottom wing or plate of the slider. This construction prevents the tearing of 20 the covering fabric.

In accordance with a third embodiment of my 25 invention, the automatic locking of the slider in position against the effect of any lateral force applied to the stringers, is accomplished by providing a plurality of indentations upon the surface or surfaces of one or both wings of the slider, which indentations provide a round-surfaced projection extending from the inner faces of the 30 wings of the slider, effective to become interposed between successive interlocking elements and thus secure the slider from unintended, self-actuated movement in a direction parallel to the opening between the interlocking elements when any force is applied to the stringers laterally of 35 the opening. For application to a slide fastener structure of the covered type, only the bottom wing or plate of the slider should be provided with the indentations.

In the accompanying drawing these embodiments of my invention are illustrated. In such drawing Fig. 1 is a plan view of a portion of a slide-fastener structure embodying my invention with part of the slider shown in section; Fig. 2 is a side view of the slider; Fig. 3 is a view similar 40 to Fig. 1 of the fabric-covered type of slide fastener structure; Fig. 4 is a side view of the slider constructed in accordance with the second embodiment of my invention; Fig. 5 is a plan view of a portion of a slide fastener to which the third embodiment of my invention is applied, the slider being shown as viewed from the bottom face thereof; and Fig. 6 is a side view of the slider shown in Fig. 5 with a portion thereof cut away to show the indentation.

55 Referring more particularly to the drawing, in which similar reference characters identify similar parts, the slide fastener structure comprises a pair of tapes or stringers having fabric portions 7 and 8 and rows of spaced interlocking 60 fastener elements 9 and 10 along their adjacent longitudinal edges, which elements are adapted to be successively brought together and progressively interlocked by means of the slider 11. The slider illustrated is constituted of spaced top and 65 bottom wings or plates 12 and 13 respectively, connected by an integral wedging and spacing portion 14 and a pull member 15 connected to the top wing of the slider by means of a bridge 16. The lateral edges of the slider wings 12 and 70 13 are bent inwardly to provide the guide flanges 17 and 18 on opposite sides of the slider and these flanges form, in conjunction with the wedging portion 14, a channel having diverging portions for receiving the fastener elements 9 and 10.

In the embodiment of my invention illustrated

in Figs. 1 and 2, dependent portions 21 and 22 and and notches 19 and 20 are incorporated.

When the slider 11 has been brought to the position in which it has interlocked the elements 9 and 10 to the length desired and any lateral pull is exerted upon the tapes or stringers 7 and 8, the projections 21 and 22 become interposed between two successive fastener elements, the lower of such successive fastener elements entering into the notches 19 and 20. As a lateral pull 10 is exerted upon the stringers 7 and 8, the heel portions of the lower of such successive fastener elements are automatically, and without any volitional movement on the part of the operator, brought into abutting relation with the lower 15 edges of the projections 21 and 22, preventing any unintended and self-actuated movement of the slider 11 and therefore separation of the interlocked fastener elements.

It is to be noted that the projections 21 and 20 22 become interposed between successive fastener elements only upon the exertion of any lateral pull upon the stringers 7 and 8, but are otherwise clear of the heel portions of such fastener elements so that free movement of the slider in performing its function of interlocking the fastener elements is not interfered with so long as the pull upon such slider is induced by a force exerted longitudinally of the slider, namely in a direction 25 parallel to the opening of the slider structure. 30

In Figs. 3 and 4 I have illustrated an embodiment of my invention particularly advantageous in its application to a slide fastener structure of the covered type. In such structure the edges of the tapes or stringers 7 and 8 extend over the 35 interlocking elements 9 and 10, so as to conceal completely the same, in the closed position of the fastener structure by the overlying strips 23, 24 formed by the edge portions of the stringers. Such strips 23, 24 are secured in place in any 40 manner, now well known, for instance, by lines of stitching (not shown).

The slider for such fastener structure is substantially like that illustrated in the first embodiment of my invention, with the exception 45 that the wing or plate of the slider arranged for movement over the covering strips 23 and 24 has its flanges 25 and 26 cut off from the upper edge of the wing to a point somewhat removed therefrom (at 27), such cut-off permitting the flange 50 to move freely over the cover-strip, the restraining of unintended movement of the slider, when lateral pull is exerted upon the stringers, being accomplished by the notches 19 and projection 21 upon the flange of the bottom plate of the 55 slider.

Another form of means effective to lock automatically the slider against unintended movement longitudinally over the interlocking elements when lateral pull is applied to the stringers, is illustrated in Figs. 5 and 6. In such embodiment of my invention the lower wing or under plate 28 is provided at the points of junction of the flanges 29 with the inclined edges 30, 31 of the slider, with indentations 32, the material of the slider wings being depressed to an extent sufficient to form the depending projection or protuberances 33 extending inwardly from such lower wing or under plate 28.

The depth of the projections 33 in Figs. 5 and 6 70 is restricted so that in the normal movement of the slider to lock or unlock the elements, there is no contact between 33 and the elements 9, 10. When, however, a lateral pull is exerted upon the stringers at or beyond the slider, the effect of

- such a pull is to twist the elements on the stringers and this brings them into contacting relation with respect to the projections 33. Once this condition has been established, i. e. where a 5 projection 33 lies in the path of the next lower element, and the element has been turned into the projection-engaging position as the result of a lateral pull on the fabric, the projections 33 lock the slider against further movement in a direction 10 tending to unlock the locked elements further down. The greater the force applied to the stringers, tending to spread them, the greater will be the extent to which the elements will extend into the region of the protuberances 33 and 15 therefore the more certain the prevention of unintended movement of the slider from its fixed position in which it holds the fastener elements interlocked becomes.
- It is to be noted that in this embodiment of my 20 invention also, as in the two first embodiments described, the provision of the means for locking the slider against unintended movement in one direction, does not, in any manner, interfere with the normal functioning of such slider. Thus, if 25 the stringers 7 and 8 are not spread apart by any force exerted laterally thereof, the indentations upon the slider have no effect upon its normal movement over the fastener elements, such indentations, and therefore the protuberances 30 extending from the under plate on the opposite face thereof, being out of the aligned positions of the fastener elements and hence the latter are unaffected by such indentations or protuberances.
- 35 The embodiment of my invention illustrated in Figs. 5 and 6 is ideally adapted for application to a covered type of fastener structure in which case the means for preventing the spreading of the stringers, and therefore the unintended movement of the slider, are provided only upon the 40 lower wing or under plate of the slider, where they cannot tear the covering fabric strips or the stitching employed in securing the same in place.
- 45 I claim:
1. A slider for a slide fastener of the type which includes a pair of stringers having rows of spaced interlocking elements along their adjacent longitudinal edges, comprising in combination a pair 50 of spaced top and bottom plates, camming flanges depending from at least one of said slider plates and means independent of manual operation of the slider for preventing the unintended self-actuated movement of the slider when forces tending 55 to spread the stringers apart are applied laterally thereto at points beyond the interlocked portions of the elements, comprising projections integral with the upper portion of and projecting
- from the surface of at least one of the slider plates toward the opposite plate, said projections being of the buttressed type, i. e. so formed that their resistance to deformation is at least as great in line with the longitudinal path of the rows of elements as in a line transverse to the length of such rows, and being disposed outside of the normal path of the outer edges of the interlocking elements but closely adjacent to such path, whereby when lateral pull is applied to the stringers 10 beyond the interlocked position of the elements, the projections will extend into the path of the elements as they tend to move from the locked to the interlocked position.
2. A slider for a slide fastener of the type which 15 includes a pair of stringers having rows of spaced interlocking elements along their adjacent longitudinal edges, comprising in combination a pair of spaced top and bottom plates, camming flanges disposed substantially perpendicular to at least 20 one of said slider plates for interlocking the elements of the fastener when the slider is moved along the stringers in the direction of its upper portion; and means for preventing the unintended self-actuated movement of the slider in 25 the other direction when forces tending to spread the slider apart are applied laterally thereto at points beyond the interlocked portions of the elements, comprising projections provided on the upper portion of the slider in alignment with the 30 camming flanges of a slider and spaced from the upper edge portions of said flanges for a distance equal to at least the space represented by the transverse dimension of one of the interlocking elements, all so assembled and arranged that when 35 40 lateral pull is applied to the stringers beyond the interlocked position of the elements the depending projections will extend into the path of the elements as they tend to move from the locked to the unlocked position.
3. A slider such as described in claim 1 in which the projections project both from the top as well as from the bottom plates of the slider.
4. A slider such as described in claim 1 in which the projections are formed in the bottom 45 plate only of the slider.
5. A slider such as described in claim 2 in which the projections are bent parts of one of the plates of the slider said projections extending toward the opposite plate of the slider and 50 the line of the bend runs in a direction which approximately parallels the longitudinal path of the fastener elements past said projections.
6. A slider such as described in claim 1 in which the projections are in the form of hollow 55 depressed protuberances.
